(57) **CLAIM**

The ornamental design for a “flip down monitor,” as shown and described.

DESCRIPTION

This application is related to U.S. design patent application No. 29/131,451 entitled “Flip Down Monitor Base” filed concurrently herewith.

FIG. 1 is a perspective view of a flip down monitor in an opened position showing the new design;

FIG. 2 is a perspective view of the flip down monitor in a closed position;

FIG. 3 is a front elevational view of the flip down monitor in an opened position;

FIG. 4 is a rear elevational view of the flip down monitor in an opened position;

FIG. 5 is a left side elevational view of the flip down monitor in an opened position;

FIG. 6 is a right side elevational view of the flip down monitor in an opened position;

FIG. 7 is bottom plan view of the flip down monitor in an opened position; and,

FIG. 8 is a top plan view of the flip down monitor.
